CHARLES A. DAME, OF PROVIDENCE, RHODE ISLAND

STRAND-WORKING MACHINE

Application filed August 1, 1928. Serial No. 296,657.

My invention relates to trigger actuated latches for movable members, of a type particularly adapted for use in a stop motion mechanism for braiding machines adapted to braid cord around a plurality of elastic cores.

While I am aware that others have provided various types of stop motion mechanisms operative on breakage of an elastic core to stop a braiding machine, so far as I am aware, none of these have actually come on the market to date. An elastic core is a very stretchable and light object and it has been hard to provide a stop motion mechanism so delicate as to be actuated merely by the breakage of said core. If a stop motion mechanism similar to the usual braiding stop motion mechanism is provided, it will tend either to break, distend or stretch the core to make the braiding uneven. By providing a trigger actuated latch means in which the trigger portion thereof is releasable on a relatively light force, and increasing the force before it actuates the stop motion mechanism, I am enabled to provide a stop motion mechanism which functions very efficiently in practice. Due to the force of the relatively heavy spring I preferably employ to actually actuate the stop motion mechanism I am able to provide a quick acting and sure stop motion mechanism for the machine if anything, quicker than any type of electric stop motion mechanisms.

A further object of my invention is to provide a stop motion mechanism of this type which may be readily connected to a braiding machine without in any respect modifying the construction thereof. I merely insert the beam for the elastic cores having the necessary parts of my stop motion mechanism attached thereto underneath the braiding machine and attach a rod therefrom to the usual stop motion mechanism of the braiding machine.

A further object of my invention is to provide a trigger actuated latch for this or any purpose which is releasable on a relatively light force to permit a relatively heavier force to act and particularly where a large force is required to release a stop motion mechanism or for any other desired purpose. I

may connect a plurality of my improved latches in series so as to increase the force sufficiently to release the stop motion or other mechanism.

These and such other objects of my invention as may hereinafter appear, may be best understood from a description of the accompanying drawings which illustrate various embodiments thereof attached to a standard multiple elastic braiding machine.

In the drawings:

Fig. 1 is a front elevation of a braiding machine with my improved stop motion mechanism attached thereto.

Fig. 2 is a side elevation thereof.

Fig. 3 is a fragmentary side elevation of certain parts of the stop motion mechanism after it has functioned to stop the machine.

Fig. 4 is a diagrammatic view illustrating the functioning of the trigger shaft and attached weight.

Fig. 5 is a diagrammatic view showing a plurality of my trigger actuated latches connected in series for stopping a particularly large and heavy braiding machine.

In the drawings, wherein like characters of reference indicate like parts throughout, 10 generally indicates a braiding machine of standard type, including the frame 12 suitably supported by the legs 14 mounted on a 80 suitable table or stand 16. The braider carriers 18 revolve as usual in the sinuous crossing tracks in the top plate 20 and are driven as usual by the gearing 22 suitably revolved by the pulley 24. Between the gearing 22 and pulley 24 there is interposed the usual clutch 26. The frame 12 is provided with the suitable holes 27 through which the elastic cores 28 may be led to have braided around them the usual cord.

While my elastic core stop motion mechanism may actuate any desired type of stop motion mechanism, I preferably so connect it to the braiding machine that it may act upon the already existing type of stop motion mechanism already built on most types of braiding machines to stop the machine. When a thread or cord in one of the braider carriers breaks for any reason, each braider carrier is provided with a weight 30 slid-

65

70

75

85

90

95

100

ably mounted on a post 32 thereof normally held up by the cord during the braiding operation and adapted to slide down the post 32 to move over the pivoted lever 34 to actuate the stop motion mechanism as the lowered weight comes adjacent to the lever 34 as the carrier winds around the sinuous crossing tracks after breaking of the cord.

36 represents the main drive shaft which has mounted thereon the driving pulley 24 and which has on its inner end the bevel gear 37. Said bevel gear 37 is adapted to mesh as usual with the bevel gear 38 loosely mounted on a revolvable upright shaft 40. Said upright shaft 40 has keyed thereto the driving gear 42. The braiding machine is provided with the usual clutch 26 which preferably includes comprising a clutch fork 44 adapted on the upward movement of the shipper handle to cause the driving gear 42 to revolve with the continuously revolving bevel gear 38. The braiding machine is normally provided with a pivoted latch 46 which normally over-laps the adjacent edge of the pivoted lever 34 which releases the clutch 26 to cause non movement of the driving gear 42.

I preferably suitably connect my elastic core stop motion mechanism to the pivoted latch 46 without in any way interfering with the functioning of the usual stop motion mechanism by means of the rod 50 so that on downward movement of the rod 50 the latch 46 will be pulled down to move the pivoted lever 34 to release the clutch 26. It is thus apparent that the only modifications of a standard braiding machine necessary are to provide the holes 27 in the frame thereof and means for attaching the rod 50 to the pivoted latch 46.

The elastic cores 52 are suitably mounted as usual on the beam 54 normally located underneath the braiding machine, said beam 54 being provided with the usual weight brake 56. The elastic cores 52 are suitably wound individually on different portions of the beam 54. Although my improved trigger actuated latch for the movable member may be actuated by a single light moving strand, as shown in the drawings, or otherwise it is preferably so constructed as to be actuated on the breakage of any one of the elastic cores 52, of which there may be eight as shown in the drawings. While any suitable type of latch means may be employed on a portion of the beam stand 58 underneath the beam 54, I preferably suitably pivotably mount the arm 60. Said arm 60 has the free outer end thereof connected to the rod 50 and an enlarged curved portion such as the disk 62 near the pivot point thereof having a notch 64 on the upper portion of the periphery thereof. I provide a relatively strong spring 66 connected to the rod 50 to move it downwards to actuate the stop motion mechanism having

the opposite end thereof suitably connected to the beam frame 58, and suitable means to release said notch means to permit the spring to move said rod. In my preferred embodiment I provide gravity operative pivotable trigger means operative to release the latch means to permit the spring 66 to move the rod 50. The trigger means includes the pivotable trigger shaft 68 normally biased against gravity by the relatively light force of an elastic core and I provide means such as a slidable weight 70 operative on breakage of said core to increase the gravity moment of said trigger shaft sufficiently to release the latch means. While any suitable type of latch means may be employed, I preferably employ the pawl 72 suitably pivotably mounted on the beam frame 58 to have an end thereof register in the notch 64 on said pivoted arm 60.

In my preferred embodiment, the latch means also includes the lever 74 suitably pivoted at 76 to the beam frame 58 adjacent said pawl having the work arm 78 adapted to abut the free end 80 of the pawl 72. The power arm 82 of said lever 74 normally projects upwardly. In the embodiment shown, the pivot of the lever 74 comprises the pivot rod 76 extending underneath the beam 54 and parallel therewith. The trigger means includes a plurality of pivoted trigger shafts 68 one for each core suitably pivoted as at 84 to an extension of the frame 58. Each trigger shaft has the spool 86 revolvably mounted on the normally raised end 88 of the power arm thereof adapted to receive the elastic core 52 to normally retain said power arm 88 in raised position. Each trigger shaft is also provided with a suitable slideway comprising the rod 90 which extends from substantially the pivot point 84 of said shaft along the power arm 88 thereof. I also provide a weight 70 having a hook 71 for mounting on said rod 90 adapted in normal position of each trigger shaft 68 during the operation of the machine to lie as shown in Fig. 4 a relatively small distance from the pivot point 84 thereof. As also shown diagrammatically in Fig. 4 on breakage of the core 52, the power arm 88 of said trigger shaft 68 will drop and after it passes the horizontal the weight 70 will slide down the power arm of said shaft 68 to increase the force of the gravity moment thereof to increase the upward force of the work arm 89 of said trigger shaft striking the power arm 82 of the lever 74 sufficiently to knock the pawl 72 out of the notch 64 to permit the spring 66 to move the rod 50 to actuate the stop motion mechanism. It is thus obvious that the latch means will release by the dropping of any individual trigger shaft 68 on the breakage of the core.

In a light braiding machine a single trigger actuated latch is sufficient to release the stop motion mechanism but particularly on

a 44 carrier or larger braiding machine in order to increase the force acting on the movable member or rod 50 sufficiently to release the stop motion mechanism, I preferably connect two or more of my spring actuated latches in series as shown in Fig. 5. In Fig. 5 the lever 74 is released as usual by the trigger shaft on breakage of a core to knock the pawl 72 out of the notch 64 in the pivoted arm 60 which will permit the relatively light spring 66 to move the rod 92. The rod 92 however, is not connected directly to the stop motion mechanism but a second spring actuated latch similar to the spring actuated latch I normally employ is interposed between said first spring actuated latch and the stop motion mechanism connection. I also suitably pivot the arm 94 to a portion of the beam frame 58 and connect the free end thereof to the movable rod 92. I also pivotably mount a second pawl 96 on said beam frame 58 adapted to have the free end thereof contacted by the pivoted arm 94. Said pawl 96 is adapted to register in a notch 98 suitably formed on the rotatable member 100 suitably pivoted at 102 to the machine and connected to the lower end of the movable member 50. Said movable member 50 is normally urged downwards by the force of the relatively heavier spring 104 connected to the lower end thereof and also to the beam frame 58. It is obvious that on depression of the movable rod 92 through the medium of the relatively light spring 66 when the trigger mechanism is released by the breakage of a core as usual, that the connected arm 94 will also be depressed to knock the pawl 96 out of the notch 98 in the pivoted rotatable member 100 to permit the relatively heavier spring 104 to depress the movable rod 50 to actuate with great force the stop motion mechanism. If it is desired to still further increase the force it is obvious that additional spring actuated latches may be connected in series.

When the trigger actuated latch has functioned to stop the machine, it is obvious that it will be necessary to re-set the pawl and trigger and suitably support the power arm of the trigger by a new elastic core. It is apparent that I have provided a very quick and sure stop motion mechanism of sufficient strength to stop the machine and normally held in raised position by the relatively light force only of a moving strand.

While I have shown my trigger actuated latch attached to a braiding machine, it is obvious that it may be employed in any case where it may be desired to move a member for any purpose on breakage of a light moving strand, or otherwise.

It is understood that my invention is not limited to the specific embodiments shown and that various deviations may be made

therefrom without departing from the spirit and the scope of the appended claims.

What I claim is:

1. In combination with an elastic braiding machine having means for continuously braiding cord around an elastic core and a stop motion mechanism, spring actuated means connected to said stop motion mechanism to actuate the same, trigger means operative to release said spring actuated means to stop the machine including a pivotable trigger shaft and a weight slidably mounted on said trigger shaft normally biased against gravity at a position near the pivot point of said trigger shaft by contact of an elastic core against the outer end of said trigger shaft and slidably on said trigger shaft to increase the gravitation of said trigger shaft sufficiently to release said spring actuated means on breakage of said elastic core. 85

2. In combination with an elastic braiding machine having means for continuously braiding cord around an elastic core and a stop motion mechanism, relatively strong spring actuated means connected to said stop motion mechanism, latch means for said spring actuated means releasable on a relatively heavy force, a trigger shaft pivoted so as to be normally biased against gravity by the relatively light force of an elastic core, and pivotable on breakage of said core to abut said latch means, and slidable means operative on breakage of said core to increase the gravitation of said trigger shaft sufficiently to strike said latch means with sufficient force to release it. 95

3. In an elastic braiding machine, in combination, means for continuously braiding cord around an elastic core, a stop motion mechanism and trigger means operative to release said stop motion mechanism including a pivotable trigger shaft and a weight slidably mounted on said trigger shaft normally biased against gravity at a position near the pivot point of said trigger shaft by contact of an elastic core against the outer end of said trigger shaft and slidably on said trigger shaft to increase the gravitation of said trigger shaft sufficiently to release said stop motion mechanism on breakage of said elastic core. 110

4. In combination with an elastic braiding machine having means for continuously braiding cord around an elastic core and a stop motion mechanism, latch means for said stop motion mechanism releasable on a relatively heavy force, a trigger shaft pivoted so as to be normally biased against gravity by the relatively light force of an elastic core and pivotable on breakage of said core to abut said latch means and slidable means operative on breakage of said core to increase the gravitation of said trigger shaft sufficiently to strike said latch means with sufficient force to release it. 125

5. In combination with an elastic braiding machine having means for continuously braiding cord around an elastic core and a stop motion mechanism, a rod connected to said stop motion mechanism, a spring connected to said rod normally urging said rod to a position to actuate the stop motion mechanism to stop said machine, a pivotably mounted arm having the free end thereof connected to said rod and an enlarged curved portion near the pivot point thereof having a notch on the periphery thereof, a pivotably mounted pawl adapted to register in said notch, a lever pivotally mounted adjacent said pawl having a work arm adapted to abut the free end of said pawl and an upwardly projecting power arm, a pivotably mounted trigger shaft having a spool revolvably mounted on the end of the power arm thereof adapted to receive the elastic core to normally retain said power arm in raised position and a slideway extending from substantially the pivot point of said shaft along said power arm, a weight mounted on said slideway adapted in normal position of said trigger shaft to be adjacent the pivot point thereof whereby on breakage of said core the power arm of said trigger shaft may drop to permit the weight to slide down the power arm thereof to increase the force of the work arm of said shaft striking the power arm of said lever sufficiently to knock the pawl out of the notch to permit the spring to move the rod to actuate the stop motion mechanism.

6. In a strand working machine having a stop motion mechanism and a movable member to actuate said stop motion mechanism, a trigger actuated latch for said movable member, comprising a spring to move said member, a pivotably mounted arm having the free end thereof connected to said member and an enlarged curved portion near the pivot point thereof having a notch on the periphery thereof, a pivotably mounted pawl having an end adapted to register in said notch, a lever pivotally mounted adjacent said pawl having the work arm thereof abutting the free end of said pawl and an upwardly projecting power arm, a pivotably mounted trigger shaft having a spool revolvably mounted on the end of the power arm thereof adapted to be held in raised position by contact with a moving strand, a weight slidably mounted on the trigger shaft slidable from normal position near the pivot point thereof down the power arm thereof on breakage of said strand to increase the gravitation of said trigger shaft sufficiently to permit the upward movement of the work arm thereof to strike said lever with sufficient force to knock the pawl out of the notch to permit said spring to move said stop motion mechanism actuating member.

65. 7. In a strand working machine having a

stop motion mechanism and a movable member to actuate said stop motion mechanism, a trigger actuated latch for said movable member normally urged in one direction, comprising a notched rotatable member connected to said movable member, a pivotally mounted pawl having an end adapted to register in said notch, pivotally mounted trigger means to release said pawl from said notch including a pivotable trigger shaft and a weight 75 slidably mounted on said trigger shaft normally biased against gravity at a position near the pivot point of said trigger shaft by contact of a moving strand against the power arm of said trigger shaft and slidable on said trigger shaft to increase the gravitation of said trigger shaft sufficiently to cause a portion of said trigger means to strike said pawl with sufficient force to knock it out of said notch to permit movement of said stop motion mechanism actuating member on breakage of said strand.

8. In a strand working machine having a stop motion mechanism and a movable member to actuate said stop motion mechanism, a trigger actuated latch for said movable member comprising a movable rod, a spring to move said rod, a notched rotatable member connected to said movable rod, a pivotally mounted pawl having an end adapted to register in said notch, trigger means to release said pawl from said notch including a pivotable trigger shaft and a weight slidably mounted on said trigger shaft normally biased against gravity at a position near the pivot point of said trigger shaft by contact of a moving strand against the power arm of said trigger shaft and slidable on said trigger shaft to increase the gravitation of said trigger shaft sufficiently to cause a portion 100 of said trigger means to strike said pawl with sufficient force to knock it out of said notch to permit the spring to move said rod, a pivotably mounted arm connected to said rod, a second pawl adapted to be contacted by said arm, a second notched rotatable member connected to said movable member, and a relatively larger spring to move said stop motion mechanism actuating movable member on release of said second pawl.

9. In a strand working machine having a stop motion mechanism and a movable member to actuate said stop motion mechanism, a trigger actuated latch for said movable member, comprising a relatively strong spring to move said member, means to latch said movable member against the force of said spring releasable on a relatively heavy force, a trigger shaft pivoted so as to be normally biased against gravity by the relatively light force of a moving strand and pivotable on breakage of said core to abut said latch means, and slidable means operative on the breakage of said strand to increase the gravitation of said

trigger shaft sufficiently to strike said latch means with sufficient force to release it.

10. In a strand working machine having a stop motion mechanism and a movable member to actuate said stop motion mechanism, a trigger actuated latch for said movable member comprising a relatively strong spring to move said member, to actuate said stop motion mechanism, means to latch said movable member against the force of said spring releasable on a relatively heavy force, and trigger means operative to release said latch means to permit the spring to move said member, including a pivotable trigger shaft and a 15 weight slidably mounted on said trigger shaft normally biased against gravity at a position near the pivot point of said trigger shaft by contact of a light moving strand against the outer end of said trigger shaft and slidable on 20 said trigger shaft to increase the gravitation of said trigger shaft sufficiently to release said latch means on breakage of said light moving strand.

11. In a strand working machine having a 25 stop motion mechanism and a movable member to actuate said stop motion mechanism, a trigger actuated latch for said movable member, comprising a movable rod, a relatively strong spring to move said rod, means to latch 30 said movable rod, against the force of said spring releasable on a relatively heavy force, trigger means operative to release said latch means to permit the spring to move said member including a pivotable trigger shaft and a 35 weight slidably mounted on said trigger shaft normally biased against gravity at a position near the pivot point of said trigger shaft by contact of a moving strand against the power arm of said trigger shaft and slidable on said 40 trigger shaft to increase the gravitation of said trigger shaft sufficiently to release said latch means on breakage of said strand, a relatively larger spring to move said movable member, means to latch said movable member 45 against the force of said spring releasable on a relatively heavy force and means operative on movement of said movable rod to release said latch means to permit the relatively heavier spring to move said movable member 50 to actuate said stop motion mechanism.

12. In a strand working machine having a stop motion mechanism and a movable member to actuate said stop motion mechanism, a trigger actuated latch for said movable member, comprising a relatively strong spring to move said movable member, to actuate said stop motion mechanism, means to latch said movable member against the force of said spring releasable on a relatively heavy force, a movable rod to release said latch means, a relatively lighter strong spring to move said movable rod, means to latch said movable rod against the force of said spring 60 and trigger means operative on breakage of a 65

moving strand to release the rod latch means to permit said light spring to move said rod to release said movable member latch means to permit the relatively heavier spring to move the movable member.

13. In combination with an elastic braiding machine having means for continuously braiding cord simultaneously around a plurality of elastic cores and a stop motion mechanism, a beam for mounting a plurality of elastic cores thereon, spring actuated means connected to said stop motion mechanism, latch means for said spring actuated means releasable on a relatively heavy force, including a latch rod extending underneath the beam and parallel therewith, trigger means operative to release said latch means to stop the machine including a plurality of pivotable trigger shafts one for each individual elastic core and a weight slidably mounted on each trigger shaft normally biased against gravity at a position near the pivot point of each trigger shaft by contact of an individual elastic core against the outer end of each trigger shaft and slidable on each trigger 80 shaft to increase the gravitation of said trigger shaft sufficiently to strike said latch rod with sufficient force to release said latch means to permit said spring actuated means to actuate the stop motion mechanism.

14. In combination with an elastic braiding machine having means for continuously braiding cord simultaneously around a plurality of elastic cores and a stop motion mechanism, a beam for mounting a plurality of elastic cores thereon, means connected to said stop motion mechanism, latch means for said means releasable on a relatively heavy force, including a latch rod extending underneath the beam and parallel therewith, trigger means operative to release said latch means to stop the machine including a plurality of pivotable trigger shafts one for each individual elastic core and a weight slidably mounted on each trigger shaft normally 90 biased against gravity at a position near the pivot point of each trigger shaft by contact of an individual elastic core against the outer end of each trigger shaft and slidable on each trigger shaft to increase the gravitation of said trigger shaft sufficiently to strike said latch rod with sufficient force to release said latch means to actuate the stop motion mechanism.

15. In combination with a strand working machine having a continuously moving strand and a stop motion mechanism, latch means for said stop motion mechanism releasable on a relatively heavy force, a trigger shaft pivoted so as to be normally biased 100 against gravity by a relatively light force of the moving strand and pivotable on breakage of a strand to abut said latch means and slidable means operative on breakage of a strand to increase the gravitation of said 110

trigger shaft to strike the latch means with sufficient force to release it.

16. In a strand working machine having a stop motion mechanism and a movable member to actuate said stop motion mechanism, a trigger actuated latch for said movable member, comprising means to move said member in a direction to actuate said stop motion mechanism, means to latch said movable member against the force of said movable means releasable on a relatively heavy force, a movable latch releasing member, means relatively lighter than said first movable member moving means to move said movable latch releasing member, a second latch means to latch said latch releasing movable member against the force of said second moving means, and trigger means operative on breakage of a moving strand to release the second latch means to permit the relative light second moving means to release said first movable member latch means to permit the first movable member actuating means to move the first movable member to actuate the stop motion mechanism.

25 In testimony whereof I affix my signature.
CHARLES A. DAME.
